UNITED STATES PATENT OFFICE.

JAMES S. LATUSS, OF BROOKLYN, NEW YORK.

DESIGN FOR A CURTAIN-CORNICE.

SPECIFICATION forming part of Design No. 15,415, dated September 16, 1884.

Application filed June 17, 1884. Term of patent 7 years.

To all whom it may concern:

Be it known that I, JAMES S. LATUSS, of Brooklyn, county of Kings, and State of New York, have invented and produced a new and original Design for Cornices, of which the following is a full, clear, and exact description, reference being had to the accompanying drawings, and to the letters of reference marked thereon.

10 This invention has relation to designs for cornices such as are employed at windows and doors in connection with curtains and other draperies.

15 Figure 1 is a front elevation, and Fig. 2 a top or plan view, of my newly-designed cornice, these two views being deemed all that is necessary to fully illustrate my design.

In both figures like letters of reference wherever they occur indicate corresponding parts. 20 B is the exterior or ornamental part of the cornice, extending above and below the part A, as indicated in the elevation, and across the ends thereof, as indicated in the plan, so as to conceal the said part A from view when 25 the cornice is in position. The exterior is ornamented at top and bottom by a series of semicircles, *a a*, on the inner sides of which is the trifoliated figure, as indicated at *b b*, leaving the margins of the cornice in the form of 30 open-work, which gives the same a light and pleasing appearance. I provide two parallel ribs or ridges or beadings, *c c*, which project outwardly from the exterior surface, as plainly shown. The plain or central band thus bound-

ed by the beadings is relieved in front by projecting knobs *d d*, located at suitable intervals, and having heads *e e*, which give a rich finish to the cornice. On each end of the cornice are ornamented knobs or projections C, considerably larger than those at *d d*, the heads 40 of these end ornaments being lightened by suitable open-work, as represented at *f f*. The ornaments C may be of the same color as the covering-strip or made to contrast therewith, as may be desired. 35

Having now fully described my design, what I claim as new, and desire to secure by Letters Patent, is—

1. The herein-described design for a cornice, consisting of the open-work ornamentation at 50 top and bottom, the parallel beadings, intermediate plain portion, projecting knobs *d d*, and end knobs, C C. 45

2. The herein-described design for a cornice, consisting of the open-work ornamentation at 55 top and bottom, showing a series of semicircles, *a a*, having inner trifoliated figures, *b b*, the parallel beadings, intermediate plain portion, projecting knobs *d d*, and end knobs, C C. 60

In testimony that I claim the foregoing I have hereunto set my hand in the presence of two witnesses.

JAMES S. LATUSS.

Witnesses:

JAMES BRENNAN,
S. T. MADDOX.
